UNITED STATES PATENT OFFICE.

JOSEPH ROY, OF PHILADELPHIA, PENNSYLVANIA.

HORSESHOE-NAIL MACHINE.

SPECIFICATION forming part of Letters Patent No. 296,461, dated April 8, 1884.

Application filed May 17, 1883. (No model.)

To all whom it may concern:

Be it known that I, JOSEPH ROY, a citizen of the United States, residing in the city and county of Philadelphia, and State of Pennsylvania, have invented a new and useful Machine for Making Horseshoe-Nails, of which the following is a specification.

The nature of my invention consists of certain constructions, combinations, and arrangement of parts, hereinafter fully explained and specifically claimed, said parts being the constituents of a horseshoe-nail machine, which, as improved by me, will produce horseshoe-nails of a superior quality in a very short time, as will be hereinafter made to appear.

The mechanism which I employ in carrying out my invention is illustrated in the accompanying drawings, in which—

Figure 1 is a top view of the entire machine as improved by me. Fig. 2 is a vertical central section through the feeding apparatus and mechanism for operating the hammers. Fig. 3 is a detail front view of the hammers and hammer-operating mechanism. Fig. 4 is a detail diagram of a portion of the mechanism for operating the hammer-checks, as will be hereinafter described. Fig. 5 is a detail diagram of the nail deflecting and cutting mechanism, as will be hereinafter described. Fig. 6 is a detail diagram of a portion of the feed mechanism. Fig. 7 is a side elevation of a cam-groove wheel, forming a portion of the feed mechanism. Fig. 8 is a diagram of the feed mechanism shown in Fig. 6, viewed from the front of the machine; and Fig. 9 is an enlarged vertical longitudinal section of the heating gas-furnace through which the nail-rod passes.

My machine comprises, in the main, a feed mechanism, (designated generally by A,) a heating gas-furnace, (designated by B,) a forging mechanism, (designated by C,) a cut-off mechanism, (designated by D,) and other mechanisms of subordinate nature, all the parts of which will be hereinafter specifically described, as they are arranged for a united action upon a suitable foundation, X. A main shaft, E, gives motion to the entire machine. It is suitably hung in ordinary bearings, e, and passed through a housing, F, which supports the forging mechanism proper. By means of two bevel-gears, e', said shaft E drives two

similar bevel-gears, e', on two upright shafts, f, hung in the housing F, and by means of two bevel-gears, e', at their upper ends these upright shafts f drive two similar bevel-gears, 55 e', on a horizontal shaft, f', hung in the upper portion of the housing F. These bevel-gears e' having all the same number of teeth, the four shafts E f f' f' revolve with precisely the same speed, and by having a driving-gear 60 at each end said shafts revolve without one-sided or diagonal strain in their bearings, and thus perform their work more steadily and with less wear than shafts driven at one end only. Each of the said shafts is provided with a double cam, f'', these four double cams being arranged in two pairs, each pair operating alternately a pair of hammers, G, they acting against short cam-arms g of the hammers in rear of the fulcra g' of the hammers. The hammers G are suitably hung in the housing F, their faces are properly shaped to give the nail the required form, and their short cam arms g are in continuous contact with bell-crank levers G', arranged in 70 pairs, each pair operated by a single spring of any desired number of leaves. The levers G' have their fulcra at g'' in the housing F, their inner arms, g'', bearing against the inner sides of the cam-arms g, and their transverse 75 arms g' overlapping each other, and the two arms of a pair being simultaneously operated by means of a spring—the horizontal pair by the spring H', and the vertical pair by a spring, H—said springs bearing, respectively, against 80 the rear arms, g', of each pair of bell-crank levers G', as seen in Figs. 1 and 2. The lower ends of the said springs H H' are held in the slotted bottom plate of a frame, H'', by a rod, h, and the tension of the said springs is adjusted by means of clasps h', having screw-shanks h'', which pass freely through the vertical end walls, h'', of the frame, and are provided with toothed wheels, h'', having inner 85 screw-threads which fit the screw-threads of the shanks. These wheels bear against the end walls, h'', and being turned properly by means of pinions h'', cause the springs H H' to work with more or less tension, as required.

At the end of the shaft E a pinion, e'', is 90 provided, which gears into a larger bevel-wheel, i, on a shaft, i', on which a pinion, i'',

transfers motion to a larger gear-wheel, I, and a grooved pulley, I', both on a shaft, i^3 . Suitable bearings, i^4 i^5 , support the shafts i^4 i^5 . The pulley I' is provided with an annular 5 groove, i^6 , which has a V-shaped deflection, i^7 , in which groove and deflected portion thereof a pin, j , of a lever, j' , is confined, being held motionless by the groove i^6 , but caused by the V-shaped deflection i^7 to make one oscillation 10 at every revolution of the pulley I'. The lever j' is loosely fitted to a shaft, j^2 , which carries a grooved feed-pulley, J, a coupling gear-wheel, j^3 , and a ratchet-wheel, j^4 . The lever j' carries a pawl, j^5 , which gears into the ratchet- 15 wheel j^4 , and gives motion to it.

Beneath the shaft j^2 a second shaft, j^6 , having also a grooved feed-pulley, J, and a coupling gear-wheel, j^3 , is provided. Both shafts j^2 and j^6 are suitably hung in a stand, J', and 20 move with the same speed as the wheels j^3 , which gear into each other and are of the same size. The nail-rod Y is seized by and between the pulleys J, and caused to pass through the heating gas-furnace B. This heating-furnace consists of a cylindrical chamber, K, with a large opening, k, at one end, and a small slotted opening, k', at the other end. The large opening k can be closed by a sliding door, k'', which has a central aperture through 25 which the nail-rod passes; and outside, in rear of the slotted opening k', a lever, L, swinging on a suitable fulcrum, l, and having a guiding and deflecting arm, is placed, through which arm the nail-rod Y passes toward the cutting-off mechanism, (designated by D.) In the said furnace B the nail-rod is heated to the proper degree of heat by means of a gas blow-pipe, K', (see Fig. 9,) which consists of an outer pipe, k', having a pointed nozzle, k'', and a suitable packing, k³, and an inner pipe, k⁴, having a pointed nozzle, k⁵, and a collar, k⁶, provided with a screw-thread. An annular nut, k⁷, with a hand-wheel, k⁸, is fitted to the collar k⁶ by means of inner screw-threads, and is kept in the same level by means of end rims, k⁹, and a clasp-arm, k¹⁰, suitably fastened to the pipe k⁵, or to some other rigid support. By this construction I am enabled to change the elevation of the inner pipe, k⁴, by simply 40 turning the hand-wheel k⁸, and set the nozzles of the inner and outer pipe closer toward or farther from each other, and thus I can furnish a lesser or greater supply of atmospheric air to a given supply of gas in my blow-pipe without changing the pressure of the gas. The pipes k³ k⁴ are also provided with stop-cocks k¹¹, for the purpose of cutting off or regulating the supply of the furnace. By moving the sliding door k'' back from the chamber K, the 45 opening k and the heated rod inside the furnace become exposed, and the rod may be examined with a view to regulating the air and gas supply and the heat, or for the purpose of allowing a momentary escape of a portion of the heat of the furnace while preparations for a regulation of the heat by the hand-wheel k⁸ are being made, and by this means prevent-

ing injury to the nail-rod by overheating. From the guide-arm of lever L the nail-rod passes by the cutting-off mechanism (designated by D) toward the forging mechanism, (designated by C,) and when the nail is completely forged by a sufficient number of blows of the hammers G that portion of the rod upon which the nail has been formed is deflected sidewise by the guide-arm of lever L and its adjuncts, so that it is caused to occupy a slightly diagonal position with respect to the center line of the furnace. This deflection of the nail-rod places it over a stationary cutter, 80 and under a cutter on a revolving wheel, I. 75

The sidewise movement of the guide and deflecting arm and the nail-rod is effected by means of the wheel I and a pin, i^9 , thereon, which pin, after a certain number of blows have been delivered by the hammers, depresses a horizontal arm, l', of the lever L and moves the guide-arm and nail-rod out of their normal positions into line with the cutting mechanism. The lever L and its guide-arm are kept in normal position by means of a stop-pin, l¹⁰, on a suitable stand, l', and a tension-spring, l¹¹. 90

The cutting mechanism consists of a cutter, l¹², swinging on a fulcrum, l¹³, on the stand l', and an L-shaped lever, l¹⁴, swinging on a fulcrum, l¹⁵, on the same stand, and a tension-spring, l¹⁶. The cutter l¹² has an oblique cutting-edge, l¹⁷, standing at a right angle to the deflected nail-rod, and beneath it has a slope, l¹⁸, against which the vertical arm l¹⁹ of the lever l¹⁴ bears; and the horizontal arm l²⁰ of said lever is provided with a pin, l²¹, which is depressed by a pin, i^9 , of the wheel I at the same time the lever L is operated. By the depression of the pin l²¹ the lever-arm l²⁰ is moved along the slope l¹⁸ of the cutter l¹², and the cutter is raised to its greatest elevation and kept there as an anvil-support to cut the nail upon, until a cutter, l²², having an oblique edge coinciding with the oblique edge l¹⁷ of the cutter l¹², and fastened to the wheel I, has descended to the nail-rod just above the cutting-edge l¹⁷ of the cutter l¹², and has cut off the finished nail from the nail-rod. The pin l²¹ is now relieved, the tension-spring l¹⁶ moves the lever-arm l²⁰ up and against the rear end of the cutter l¹², which is thereby lifted, while the cutting-edge l¹⁷ is lowered out of the range of the horizontal hammers G, and the next forging 100 operation can be performed without hindrance from cutter l¹². 115

While the nail is being cut from the rod, all of the hammers G are held apart by forked checks M M', suitably hung in guides m on the housing F, and caused to come into action 125 just when the nail is finished by the following-described means: The vertical check M of the horizontal hammers is provided with a pin, m', which is located in a slot, n, of a lever, N. This lever n is fastened to a shaft, n', suitably hung in uprights n², the end of which shaft is provided with a lever, n³, standing in the range of a cam, i¹¹, on the pulley I'. The horizontal check M' of the vertical hammers G has two 130

collars, m^2 , provided on its shank m^3 , between which the forked head n^4 of a lever, N' , is confined. The lever N' is supported on a fulcrum, n^5 , of one of the uprights n^2 , and it has 5 another forked head, n^6 , at its opposite end, which is slotted, as at n^7 , for the admission of a pin, n^8 , on the end of another lever, N^2 . This lever N^2 is fastened to a shaft, n^9 , which is suitably hung in the uprights n^2 , and is at its 10 other end provided with a lever, n^{10} , which stands in range of the cam i^{11} of the pulley I' . A tension-spring, m^4 , keeps the lever N and check M in normal position, and a tension-spring, m^5 , bearing against one of the collars 15 m^2 , keeps the horizontal check M' in position.

The operation of my machine is, in brief, the following: The nail-rod, which may be straightened or kept straight by an ordinary mechanism attached to the machine, is inserted into 20 the feed mechanism and heating-furnace by simply pushing it forward by hand. The blast of the blow-pipe is ignited and the rod Y allowed to become sufficiently heated, at which moment the power-shaft of the machine is 25 started. Just as the nail is finished, the hammers are checked by the means hereinbefore described, and the guide-arm of lever L deflects the nail-rod sidewise in line with the cutting mechanism, and immediately there- 30 upon the nail is cut off and drops into a suitable receiver below. After this the feed mechanism moves the nail-rod along, so that a proper portion of its length lies within the range of the blows of the hammers, and the checks are 35 withdrawn by the springs m^4 m^5 from the hammers, and the hammers, having become free, repeat the operation of forging a nail, which, when finished, is cut off in the same manner as before described, and in this manner the 40 operation continues.

In the manufacture of forged horseshoe-nails it is very important that the part of the rod which is being formed into nails shall be heated equally throughout its length and thickness, 45 and experience has proved that this can only be successfully accomplished by means of a gas-heated furnace wherein the metal is kept enveloped in a free flame, the force and heat of which are as nearly as possible unvariable—a result 50 which cannot well be secured with furnaces which are heated by ignited coal or other solid fuel from the mass of which the flame or hot-blasts are brought in contact with the nail-rod, such flame or hot-blasts having a variant 55 effect according to the condition of the mass of fuel from which it or they are obtained. Again, it is very essential that the blows of the respective hammers shall all be equal, in order that the nails formed shall be uniform 60 on each side of their longitudinal center and at their head and point, and also their construction be perfect throughout.

To accomplish the desired results above mentioned in a better manner than has been done heretofore, I have devised the improvements hereinbefore described.

With the compound blow-pipe made adjust-

able, and used in connection with the gas-heated furnace, as I have shown, a great amount of heat with less consumption of gas 70 can be obtained, and a regular supply of air under perfect control necessary for the uniform combustion of the gas maintained, and while the construction of the gas-heating furnace and blow-pipe is such that after the 75 same have once been adjusted for a given character of work it seldom, under ordinary circumstances, becomes necessary to change the adjustment during a run of the machine, still, in case of such necessity, a readjustment 80 can be effected instantly.

With two pairs of hammers, each pair operated by a single central spring, which is brought into action by elbow-crank levers G' , cams, shafts, and gears, in the manner illustrated in my drawings, a uniform blow from each of the hammers of a pair of hammers is always produced, and thus the nail-rod is kept perfectly straight, and a perfectly-formed body with respect to the head of the nail always formed. The central arrangement of the springs, together with having one spring, thus arranged, act upon the levers of the hammers, enables me to place the parts in very accessible positions, and to regulate the springs so 95 as to equalize the force of the hammers on each side of the nail-rod to the greatest nicety, and to move a pair of hammers simultaneously with the greatest precision. This arrangement also avoids loose motion, and enables me 100 to repair parts of the machine without the necessity of disturbing the whole mechanism; and with my arrangement of the revolving and vibrating cutters and deflecting mechanism, the stationary cutter is so located as to be 105 protected against the influence of the heated rod while the forging operation is proceeding, it being placed a sufficient distance in rear of the furnace and to one side of the heated part 110 of the rod to prevent it becoming intensely and injuriously heated. Further, a cleaner cut can be effected by deflecting the rod sidewise, and giving the stationary and revolving cutters obliquely-set cutting-edges, and imparting a slight upward movement to the stationary cutter, so as to bring it in contact with the deflected nail-rod, and have it form a solid support therefor during the cutting-off operation, thus expediting the cutting off of the nail, and preventing the formation of a ridge 120 on the head of the nail, as in machines where the rod is depressed by the revolving cutter, in order to rest upon its cutting-support.

The other advantages derived from my constructions and combinations having been made 125 apparent from my foregoing specification, the same need not be specially mentioned here.

I do not desire it to be understood that I claim the combination of a pair of swinging hammers and a spring, as my combination 130 comprises a pair of swinging hammers, a pair of levers, and a single spring acting upon both of the levers, and through these levers upon the two hammers at the same instant. I am

aware that in Letters Patent No. 98,707 two hammers constituting a pair have been coupled together by means of a frame and pin and oblong slot, and thus coupled have been acted upon by a spiral spring attached directly to the jaw-arm of one of the hammers of the pair; but this combination lacks the levers of my combination, and is therefore totally different in principle of operation therefrom. Neither do I wish to be understood as claiming the combination of a slider, a spring, and swinging hammers, as my combination comprises swinging hammers, a spring, and a pair of levers, which, by a swinging action, operate upon the hammers when the spring acts upon them.

I am aware that in Letters Patent No. 228,220, granted to me June 1, 1880, a pair of hammers, a slider, and a spring are shown in combination. This combination, by reason of employing a slider which has been found to be inoperative on account of the crystallization of metal under constant vibration, and frequent breakage after a few hours' use, is also totally different in principle from the combination comprising a pair of swinging levers.

What I claim as my invention, and desire to secure by Letters Patent, is—

1. The combination of a pair of swinging hammers, suitable means for operating said hammers, a pair of levers, G', and a spring, whereby the hammers are caused to exert simultaneously equal blows upon a nail-rod, substantially as described.

2. In a nail-machine, the combination of two pairs of swinging spring-hammers, each hammer having a cam-arm, g, with shafts E f f f', arranged in a quadrangle, each provided with a cam, f², and two driving gear-wheels, e'—one on each side of the cam—and with the springs H H' and levers g', substantially as and for the purpose described.

3. In combination with a gas-furnace, B, four swinging hammers, G, cams f², four pairs of gear-wheels, e', four bell-crank levers, G', two central springs, H H', acting, respectively, on the respective pairs of bell-crank levers and causing these levers simultaneously to operate upon two hammers of a pair, and each pair of said hammers being thus made to act alternately upon an iron rod supported and guided by the furnace, and constantly and uniformly heated by the flame of the same, substantially as described.

4. In combination with the hammers and levers of a nail-machine, the frame H², clasps h', having screw-shanks h² and nut-wheels h⁴, and the springs H H', substantially as and for the purpose described.

5. The combination, with the forging-hammers and gas-furnace of a nail-machine, of the cutter l⁵, having a sloping surface, l¹, and pivoted to a support of the nail-machine, the

spring lifting-lever l⁷, and wheel I, having a corresponding cutter and an actuating-pin, i⁹, 65 substantially as and for the purpose described.

6. The combination, with the forging-hammers and gas-furnace, of the wheel I, provided with an oblique-edged cutter, i¹⁰, and with actuating-pins i⁸ and i⁹, the oblique-edged cutter 70 i⁵, and means for moving the end of the nail-rod obliquely sidewise for cutting it off and lifting and holding the cutter i⁵ up and in contact with the nail-rod, and readjusting the nail-rod and said cutter to their original position after 75 the nail is cut off, substantially as and for the purpose described.

7. The combination, in a nail-machine, of swinging cutter l⁵, having a sloped surface, l¹, spring-lever l⁷, having an upright arm, l², and 80 pin l⁴, and wheel I, having a corresponding cutter and a pin, i⁹, substantially as and for the purpose described.

8. The combination, in a nail-machine, of the cutting-off mechanism D, comprising means 85 for elevating and lowering the stationary cutter, with the deflecting and readjusting spring-lever L, substantially as and for the purpose described.

9. In a nail-machine, the combination, with 90 forging mechanism C, of a gas-furnace, B, having openings k k', door k², and gas blow-pipe K', comprising an outer pipe, k³, having a pointed nozzle, k⁴, and an inner pipe, k⁶, having a pointed nozzle, k⁷, and means for regulating the said gas blow-pipe, substantially as and for the purpose described.

10. The combination, with the furnace, the cutting-off mechanism, and forging-hammers, of grooved wheel I', having the V-shaped deflection i¹, grooved feeding-rolls J, gears j³, ratchet-wheel j⁴, pawl j⁵, pawl-lever j', and pin j, substantially as and for the purpose described.

11. The combination, in a nail-machine, of 105 the grooved wheel I', having the V-shaped deflection i¹, grooved feeding-rolls J, gears j³, ratchet-wheel j⁴, pawl j⁵, pawl-lever j', and pin j, substantially as and for the purpose described.

12. The combination, with forging-hammers G, of the checks M M', wheel I', having cam I¹¹, and the intermediate connecting mechanism—to wit, levers n³ n¹⁰, shafts n⁷ n⁹, and levers N N' N²—substantially as described.

13. In a nail-machine, the combination, with a single centrally-operating power-spring, of a pair of bell-crank levers, a pair of swinging hammers, a gas-furnace provided with a gas blow-pipe, and a feeding mechanism, substantially as and for the purpose described.

JOSEPH ROY.
